EDUCATIONAL TOY

Florence C. Louis, Chicago, Ill.

Application April 30, 1953, Serial No. 24,773

Term of patent 14 years

(Cl. D25—1)

To all whom it may concern:

Be it known that I, Florence C. Louis, a citizen of the United States, residing at Chicago, in the county of Cook and State of Illinois, have invented a new, original, and ornamental Design for an Educational Toy, of which the following is a specification, reference being had to the accompanying drawings, forming part thereof.

Fig. 1 is a front perspective view of an educational toy, showing my new design in closed position;

Fig. 2 is a front elevational view thereof in open position;

Fig. 3 is a rear elevational view thereof in open position.

Fig. 4 is an exploded view of the side of the leaves which shows the stars; and

Fig. 5 is a similar view of the other side thereof.

The dominant features of my new design are shown in solid lines in the drawing.

I claim:

The ornamental design for an educational toy, as shown and described.
